US00D533862S

(12) **United States Design Patent** (10) **Patent No.:** **US D533,862 S**
Jinde (45) **Date of Patent:** **** Dec. 19, 2006**

(54) **VOICE RECORDING/REPRODUCING APPARATUS**

(75) Inventor: **Masaru Jinde**, Sagamihara (JP)

(73) Assignee: **Olympus Imaging Corporation**, Tokyo (JP)

(**) Term: **14 Years**

(21) Appl. No.: **29/239,765**

(22) Filed: **Oct. 4, 2005**

(30) **Foreign Application Priority Data**

May 10, 2005 (JP) 2005-013351

(51) **LOC (8) Cl.** **14-01**

(52) **U.S. Cl.** **D14/167**

(58) **Field of Classification Search** D14/167, D14/154, 168, 188, 496, 156, 160, 161, 162, D14/163, 164, 165, 192; D16/208; D26/38; 455/351, 350

See application file for complete search history.
